LOUIS WILPUTTE, OF NEW ROCHELLE, NEW YORK, ASSIGNOR OF TWO-THIRDS TO
ALICE A. WILPUTTE, OF NEW ROCHELLE, NEW YORK.

COKE-OVEN-WALL CONSTRUCTION.

1,399,595.

Specification of Letters Patent.

Patented Dec. 6, 1921.

Application filed October 14, 1921. Serial No. 507,610.

To all whom it may concern:

Be it known that I, Louis WILPUTTE, a citizen of the United States, and resident of New Rochelle, in the county of Westchester and State of New York, have invented certain new and useful Improvements in Coke-Oven-Wall Constructions, of which the following is a specification.

My present invention relates to coke ovens of the well known and widely used type in which each oven battery comprises a plurality of horizontally elongated coke oven chambers, each adjacent pair of which are separated by a heating wall formed with flue passages through which the heating gases flow. In this type of oven as heretofore constructed it has been found practically impossible to prevent leakage between the oven chambers and the flue spaces in the end portions of the adjacent heating walls. The brick work forming the ends of the heating wall is subjected to temperatures which average lower, and fluctuate more than the temperatures to which the bodies of the heating walls are subjected, and the resultant relative expansion and contraction of the bricks in the end portions of the heating walls tends to open the brick work joints. The mechanical stresses to which the brick work at the ends of the heating wall is subjected in discharging the ovens and in removing and replacing the oven doors also tends to loosen and open the joints. The gas leakage thus caused is objectionable as it involves a wastage of gas and by-products and interferes with the desired uniformity in oven heating.

The general object of the present invention is to provide a special construction at the ends of the heating walls which will eliminate or substantially minimize leakage between the oven chambers and the flue spaces in the oven wall. In carrying out my invention I employ metallic flashplates or armor and so shape this metallic armor and the adjacent brick work that the armor clamps the bricks forming the end and adjacent side portions of each heating wall together, and thereby prevents the corresponding joints from opening under the normal operating conditions to which they are subjected. The armor employed may also serve the purpose for which armor has heretofore been placed on the ends of the oven heating walls; namely of protecting

the brickwork from water and mechanical injuries and to form doorway frames for the oven doors.

The various features of novelty which characterize my invention are pointed out with particularity in the claims annexed to and forming a part of this specification. For a better understanding of the invention, however, and the advantages possessed by it, reference should be had to the accompanying drawings and descriptive matter in which I have illustrated and described preferred embodiments of my invention.

Of the drawings:

Figure 1 is an elevation of a portion of a coke oven battery;

Fig. 2 is a section taken on the line 2—2 of Fig. 1 but on a smaller scale;

Fig. 3 is a partial sectional plan on the line 3—3 of Fig. 1; and

Figs. 4, 5, 6 and 7 are sectional plans illustrating modified forms of construction.

In the drawings and referring first to Figs. 1, 2 and 3, I have shown a portion of a coke oven structure which, in its general form, is of the type now in most common use in large capacity by-products coke ovens. This coke oven structure is provided with horizontally elongated coking chambers A separated by heating walls in which are formed vertical heating flues B. The sides of the heating walls are formed by the so-called liner bricks C and C' and the adjacent flues are separated by walls formed by so-called bottle bricks D. The end flue B in each heating wall has its outer wall formed by bricks E. The bricks C and D may be of the usual form, but the bricks C' have their outer edges beveled at C² for engagement by the correspondingly beveled shoulders E' of the bricks E, and the latter are formed with tongue portions E² which extend between and are engaged by the flat inner sides of the adjacent bricks C'. The shoulders C² of the bricks C' at the two sides of each heating wall end are oppositely beveled so that the shoulders E² of the bricks E hold the bricks C' engaged by them against the tongue portion E². With this arrangement a relatively long joint I is formed between each brick C' and the corresponding brick E and the portions of these joints between the inner sides of the bricks C' and the tongue portions E² of the bricks are prevented from opening by the clamp-

ing action of the shoulder E' of the bricks E² exerted against the beveled surfaces C² of the bricks C'. To make this clamping action permanently effective, and to minimize the tendency of the brick shoulders E² to break away from the bodies of the bricks, and to minimize the consequence of such breakage in case it occurs, the outer faces of the bricks E and the sides of the shoulders E² of the bricks E forming each end heating wall are incased in a trough shaped metallic flashplate or reinforcing member F ordinarily made of cast iron. The flashplates F are engaged and held against movement away from the oven structure by the usual oven buckstays G. The flashplates form the sides of the doorways at the ends of the oven chambers, and are shaped to correspond to the type of door employed.

In the particular door and doorway construction illustrated in Figs. 1, 2 and 3, the doors H employed are shaped to move freely between the edges of the flashplates, and the metallic frame H' of each door and the adjacent flashplate edges are so relatively shaped as to provide a narrow trough shaped groove J in which the usual joint luting material may be placed. Preferably the doorways are provided with metallic sills at their bottoms, and metallic lintels K connect the flashplates at the tops of the doorway, and the doors are secured in place by locking bars L engaging brackets G' carried by the buckstays G. The special door construction illustrated and the shaping of the flashplates to conform to this door construction, although novel with me, is not claimed herein, but is claimed in my co-pending application, Serial No. 437,647.

In the modification shown in Fig. 4, each of the bricks E of the construction shown in Figs. 1, 2 and 3, is replaced by two bricks EA and EB each of which is formed with one shoulder E', and a portion of the tongue E². In Fig. 4 I have illustrated a modified form of door HA, and a flashplate GA externally shaped to provide a shoulder G¹⁰ against which a portion of the metallic frame of the door HA abuts, at the inner or bottom edge of the trough provided to receive the luting material.

In the modification shown in Fig. 5, the bricks EC forming the outer walls of the end flues B are rectangular blocks which fit between the liner bricks C', and the latter are recessed at their outer corners as indicated at C³ to receive the sides of the trough shaped flashplates GB which, in this construction, not only abut directly against the recessed sides of the bricks C' but also against the outer edges of those bricks.

The construction illustrated in Fig. 6 differs from that shown in Fig. 5 in that the blocks EC project out beyond the outer

edges of the bricks C' and small rectangular bricks ED are interposed between the ends of the bricks C' and the flashplates GC, which are shaped to fit against the outer faces of the bricks EC and ED, and parts 70 of the ends of the bricks C'.

In the modification illustrated in Fig. 7 each of the bricks EF at the end of heating wall each comprises a tongue portion E¹⁵ extending between the liner bricks C', and, 75 shoulders E¹⁰ which abut against the outer ends or edges of the bricks C'. In this construction, however, the outer faces or edges of the bricks C' and the shoulders E¹⁰ are beveled, not as shown in Fig. 3 but in the 80 opposite direction, and the bricks C' are held against the tongue portions E¹⁵ of the bricks EF by direct engagement of the edges of the trough shaped flashplates GD with the liner bricks C', as in the constructions 85 illustrated in Figs. 5 and 6. In Fig. 7, the outer edges of the elongated curved joints IA between the bricks C' and EF are directly sealed by the flashplates GD. The special features of construction by which the 90 form of my invention shown in Fig. 7 is differentiated from the forms shown in Figs. 3, 4, 5 and 6 are claimed in my co-pending application, Serial No. 437,647, referred to above.

In the normal contemplated mode of constructing a coke oven comprising the improvements disclosed herein, the flashplates are set in place before the heating walls are built, and the bricks at the ends of the heating walls are laid against the flashplates thus insuring the proper initial relative arrangement of bricks and flashplates. When thereafter the ovens are heated up and the parts contract and expand with the varying 105 temperatures to which they are subjected in operation, the buckstays at the opposite ends of each heating wall which are connected by the usual tie rods (not shown) hold the flashplates at all times snugly against the 110 ends of the heating wall. In consequence of this and the special shaping and arrangement of the flashplates and adjacent brick work, the flashplates at all times positively hold the liner bricks at the sides of each 115 end flue B against the portion of the end wall bricks between them.

As a result while relative expansion and contraction of the parts may cause movement in vertical planes of the liner bricks 120 relative to the end wall bricks clamped between them, the liner bricks cannot spread and open the joints between them and the end wall bricks. This practically eliminates leakage between the end flues and the oven 125 chambers since the leakage paths are comparatively long, and with the bricks at the opposite sides of the joints held firmly together the joints, in case leakage develops, are quickly resealed by dust or residue car- 130

ried into the joints by the gases leaking therethrough.

While in accordance with the provisions of the statutes I have illustrated and described the best form of my invention now known to me, it will be apparent to those skilled in the art that changes may be made in the form of the apparatus disclosed without departing from the spirit of my invention as set forth in the appended claims, and that certain features of my invention may sometimes be used to advantage without a corresponding use of other features.

Having now described my invention what I claim as new and desire to secure by Letters Patent, is:

1. In a coke oven structure comprising coking chambers and interposed hollow heating walls, the improvement which consists of brickwork forming the outer end and the side walls of the flue spaces in the ends of the heating walls and metallic armor for the ends of the heating walls, said armor and brickwork being so relatively arranged and disposed that the armor positively holds the side wall bricks against spreading.

2. In a coke oven structure comprising

coking chambers and interposed heating walls formed with vertical heating flues, the combination with bricks forming the side walls of each heating wall end flue, of bricks interposed between the side wall bricks of each end flue to form the outer end wall of the flue, and metallic armor for the ends of the heating walls arranged to positively hold the side wall bricks against the interposed bricks.

3. In a coke oven structure comprising coking chambers and interposed flue heating walls, the improved heating wall end construction comprising spaced apart liner bricks having their outer ends oppositely beveled and end wall bricks comprising tongue portions interposed between the liner bricks and laterally projecting shoulders undercut to fit against the beveled ends of the liner bricks and a trough shaped metallic member incasing the outer faces and the side edges of the shoulders of the end wall bricks.

Signed at New York, in the county of New York and State of New York this 11th day of October, A. D. 1921.

LOUIS WILPUTTE.
